UNITED STATES PATENT OFFICE.

WILHELM ALBRECHT, OF DETROIT, MICHIGAN, ASSIGNOR TO WM. ALBRECHT & CO., OF SAME PLACE.

VELOCIPED.

SPECIFICATION forming part of Letters Patent No. 229,655, dated July 6, 1880.

Application filed February 5, 1880.

To all whom it may concern:

Be it known that I, WILHELM ALBRECHT, of the city of Detroit, in the county of Wayne and State of Michigan, have invented an Improvement in Three - Wheel Velocipedes, of which the following is a specification.

The nature of this invention relates to new and useful improvements in the construction of three-wheel velocipedes; and the invention consists in the peculiar construction of the frame and its combination with the operating parts, said frame being so constructed and adapted that upon it may be built the figure of a horse, substantially as more fully hereinafter described.

Figure 1 is a perspective view, showing my improved velocipede ready for market. Fig. 2 is a perspective view, with the figure of the horse removed, showing the construction of the frame. Fig. 3 is a vertical cross-section on the line *xx* in Fig. 2.

In the accompanying drawings, which form a part of this specification, A represents the forward and driving wheel, secured to the double crank-axle B, at each end of which are journaled the rolling pedals C. Journaled upon this axle, and inside the cranks, is the frame, composed of two vertical bars of iron, D, with representations of the hoofs E of a horse immediately above and resting upon the top of said axle. The upper ends of these bars are connected by a lateral bar, F, and secured to this latter bar is a smaller frame, G, through the top of which and the chamber formed between it and the plate F passes the steering - standard H, the lower end of which is secured to the plate F, and to the upper end of this standard is secured the guiding-lever I.

The forward end of the reach J is pivotally secured to the guiding-standard H within the chamber K, and extends to the rear, and is provided upon its lower face with the intermediately-folded flanges L.

M represents the rear axle, upon the ends of which are secured the wheels N. To this axle, and between the wheels, by means of suitable boxes O, is journaled a metallic frame composed of the flat bars P and the cross-bar

Q, the bars P terminating in representations of 50 horses' hoofs R.

The forward end of the cross-bar Q terminates in a slotted lip or slide, S, which slips within the flanges L of the reach J, where it is secured by a bolt, T.

By this construction the frames P P Q and D D F can be longitudinally adjusted, the one on the other, so that the seat of the velocipede may be made longer or shorter, as desired, to adapt it to riders of different sizes 60 and different lengths of leg.

It will be noticed that in their general outline the bars D P have a resemblance to the general outline of the front and hind legs of a horse.

Upon the reach of the device, constructed as above described, and secured thereto, is a stiffener-board, U, (shown in outline in Fig. 2,) extending forward and recessed, as shown in that figure, to cover and inclose the connection between the reach and the steering-gear. This stiffener forms the base upon which is built and secured the form of the horse, as shown in Fig. 1, with the steering shaft or standard H projecting through the 75 shoulders and neck. Legs cut from wood, of the proper shape, are secured to the bars D P, the lower ends of which rest upon the offsets a a of the hoofs. The whole form of the horse, whether it be made entirely of wood or 80 of a stuffed body, is then covered, in the usual manner of covering hobby-horses, with the skin of any animal with the hair on. Those portions of the skin which cover the legs inclose also the metallic straps which form a 85 part of the legs, and being applied wet, in shrinking assist materially in confining the wooden leg to the iron part.

If the body is entirely built of wood and secured to the base and frame as described the 90 skin-covering may be omitted and the outside painted, as desired.

What I claim as my invention is—

1. In a velocipede, the combination of the frame P P Q, having the slotted slide S, with 95 the frame D D F, pivotally secured to the reach, and reach J, provided with the folded flanges L, whereby said frames can be longi-

tudinally adjusted upon each other, substantially as described, and for the purpose set forth.

2. The combination, with the frame D D F,
5 provided with the frame G, having chamber K
and tube a' , with a square central orifice, of the
standard H, with its upper part square and
lower part round, pivoted reach J, and han-
dle I, substantially as described, and for the
10 purpose set forth.

3. The combination of the adjustable frame

P P Q, having the slotted slide S, frame D D
F, having projections a and axle-boxes O,
frame G, having chamber K and tube a' ,
reach J, having flanges L, stiffener U, and 15
standard H, substantially as described, and
for the purpose set forth.

WILHELM ALBRECHT.
